UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

ROTATING MECHANISM FOR ROCK DRILLS.

Application filed January 2, 1920. Serial No. 349,018.

To all whom it may concern:

Be it known that I, ELMER G. GARTIN, a citizen of the United States, residing at Claremont, in the county of Sullivan and State of New Hampshire, have invented certain new and useful Improvements in Rotating Mechanism for Rock Drills, of which the following is a full, clear, and exact specification.

10 My invention relates to rotating mechanism for rock drills.

It has for its object to provide an improved rotating mechanism which is compact, enabling reduction in the length of the motor, and which is provided with manual control means for rendering it operative or inoperative at will. Another object of my invention is to provide an improved rotating mechanism of the type wherein the ratchet 20 portion thereof is in the opposite end of the tool from the drill steel and accordingly subjected to shock to a minimum degree. A further object of my invention is to provide an improved manual control mechanism of 25 such form as automatically to permit slipping of the rotating mechanism in the event of sticking of the steel in a crack or for any other reason.

In the accompanying drawings I have 30 shown, for purposes of illustration, one embodiment which my invention may assume in practice.

In these drawings,—

Fig. 1 is a horizontal longitudinal section 35 through the motor on the line 1—1 of Fig. 3, certain details being omitted and the manual control lever being in the opposite position.

Fig. 2 is a vertical longitudinal partial 40 section through the motor on the line 2—2 of Fig. 3, certain parts being shown in elevation.

Fig. 3 is an elevation of the rear end of the motor embodying my invention.

45 Fig. 4 is a transverse section on the line 4—4 of Fig. 2.

Fig. 5 is a transverse section on the line 5—5 of Fig. 2.

50 Fig. 6 is a detail perspective view of a part of my improved construction.

In this illustrative construction I have shown my improved rotating mechanism embodied in a drill of a well known commercial type. As my invention relates primarily 55 to the rotating mechanism proper, it will

suffice to state that the motor consists of a cylinder casing 1, having a bore 2 therein, and of a piston 3 which is reciprocated in the cylinder under the action of pressure fluid distributed through any desired port 60 arrangement, the cylinder being closed at its front and back ends respectively by plates 4 and 5.

A chuck housing 6, suitably formed to receive the tool chuck 7 and the mechanism for the immediate transmission of rotation to the chuck is secured to the front head 4. The chuck 7 consists of a sleeve having a suitable tool receiving member 8 secured 65 therein, and is provided at its rear end with 70 an enlarged collar-like extension 9 on which are formed a series of gear teeth 10.

To the back plate 5 is secured a second housing 11 which is provided with a throttle valve 12 controlling the supply of pressure 75 fluid to suitable ports in the motor, with the connections 13 for the cleansing fluid supply, and with the mounting 14 for the manual feed controlling handle 15, but as these do not per se relate to my invention, their detail construction is not disclosed. This housing 11 is also suitably cored out and machined to provide a space for the ratchet and pawl and other portions of my rotating mechanism to be later described. The front 80 and back plates and the front and back housings are held in assembled relation with the cylinder by means of suitable tie bolts 16 and nuts 17.

Rotatably mounted upon one of the tie 90 bolts 16 is a sleeve 18 which has formed upon it at its front and rear ends pinions 19 and 20 adapted respectively to mesh with the gear teeth 10 formed upon the chuck sleeve and with a series of teeth, hereinafter 95 described, forming a part of the rotating mechanism at the rear end of the cylinder.

The mechanism which I have provided for the transformation of reciprocating motion of the piston to rotary motion for rotating the drill is of the type which provides a step by step rotation of the drill steel during the return stroke of the piston and is adapted to cause a step by step rotation of the piston.

A sleeve 21 is rotatably mounted in an opening 22 in the back plate 5. This sleeve is provided with an enlarged portion 23 which has formed upon its periphery a series of teeth adapted to mesh with the teeth of pinion 20 and to rotate the sleeve 18. The 110

sleeve 21 is also provided with a forward extension 24 projecting into the piston which is bored out as at 25 to receive the same. Screwed into the rear end of the piston and 5 suitably secured is a bushing 26 which is formed with straight longitudinal grooves 27 to cooperate with a series of straight tongues 28 formed in the forwardly extending sleeve portion. The tops of the tongues 10 28 are dished to permit the flow of pressure fluid into and out of the bore 25 of the piston. The result of this construction is that the portion 23 of the sleeve is caused at all 15 times to bear a fixed relation to the piston and to rotate therewith. Suitably secured at the forward end of the bore 25 is a second bushing 31 having a rearwardly extending portion provided with a series of spiral grooves 32. Rotatably mounted upon a hub 20 member 33, secured centrally in the hollow of the rear housing member 11 is a rifle bar 34 having spiral tongues 35 to engage the spiral grooves 32 formed in the bushing 31. At its rear end the rifle bar is provided 25 with an enlarged portion 36 forming a mounting for the pawls 37 (see Fig. 4). These pawls cooperate with ratchet teeth 38 formed in the inner surface of a sleeve member 40 located between the portion 23 of 30 the sleeve 21 and the pawl mounting 36. The sleeve member 40 is secured to and formed integral with an annular member 41 which is rotatably mounted in the extreme back end of the cored out portion of the housing 35 11. This annular member is provided with an annular under-cut groove 43 opening through its rear end, in which groove is located in freely slidable relationship the head 44 of a manual control member 45. This 40 head is shaped to fit the groove loosely and be slidable there in, but to be prevented from rotation by the sides of the groove (see Fig. 6). This control member is formed with a 45 threaded stem 46 which is freely slidable through the rear head of the housing member 11 and provided with a suitable nut 47 to which is adjustably attached a manual control lever 48. By means of the threaded connection between the stem 46 and the nut 47, it is possible by movement of the control 50 lever 48 to cause the head 44 to bind frictionally with the annular under-cut groove 43. I have shown the stem 46 and nut 47 provided with a right hand thread, but it will be obvious that a left hand thread could be used, the controlling motions being reversed. The attachment of lever 48 to nut 47 consists of a series of interlocking teeth 49, the parts being held in engagement by a 55 nut 50. Should wear occur in the locking mechanism, all that is necessary to take up the wear is to remove the nut 50 and change the position of lever 48, with respect to nut 47.

60 65 The operation of my device is as follows;

Assuming the control lever 48 to be in released position, i. e., in a position approximately ninety degrees from that shown in Fig. 3, the motor can operate and the piston reciprocate without causing rotation of the 70 tool as the spiral toothed connection 32, 35 between the rifle bar and the piston will cause the rifle bar to rotate the member 40 idly, the friction incident to this rotation being much less than the work necessary 75 to the rotation of the tool. If it be desired to cause the tool to rotate, the lever 47 is turned in a clockwise direction causing the head 44 to press the member 41 tightly 80 against the back end of the housing 11, the nut 47 drawing the stem 46 rearwardly by this movement. This prevents rotation of the ratchet member and accordingly upon reciprocation of the piston, the spiral groove connection thereof with the rifle bar will 85 cause an intermittent rotation of the piston, as the rifle bar will be free to turn upon the down stroke of the piston, but will be prevented by the pawls from turning upon a 90 backward stroke. The rotation of the piston will be transmitted to the sleeve member 21 by the straight tongue and groove connection between the piston and the sleeve. The piston will accordingly impart its rotation to the sleeve 21 which will in turn by its toothed 95 portion 23 cause rotation of the pinion 20, the sleeve 18, the pinion 19, and the drill chuck by means of the teeth 10. As long as the member 41 is prevented from turning, it 100 will be obvious that a step by step rotation of the drill steel proportional in speed to the speed of the piston will result. All that is necessary to do to cause a cessation of the rotation is to release the frictional grip of the head 44 upon the member 41. A variable 105 speed of drill steel rotation may be obtained by regulating the pressure applied to the friction member.

Should the drill steel stick during 110 rotating operation, there will not be a breakage of the parts of my rotating mechanism or a stripping of the gears as the frictional lock of the member 41 is such as to permit an extraordinary twisting torque to cause 115 slipping of the parts before the breaking point of any of my elements is reached.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure 125 by Letters Patent is:

1. In a motor, a cylinder, a hollow percussive piston therein, cooperating means carried by said cylinder and extending into said piston for causing rotation of the lat.

ter, a chuck, and chuck rotating means including an element extending into the interior of said piston and having a straight tongue and groove connection therewith.

5. 2. In a motor, a cylinder, a hollow percussive piston therein, cooperating means carried by said cylinder and extending into said piston for causing rotation of the latter, a chuck, and chuck rotating means including an element extending into the interior of said piston from the rear end thereof and having a straight tongue and groove connection therewith.

10. 3. A motor comprising a cylinder, a hollow rotating piston reciprocable therein, an intermittently rotating element having a portion extending into the interior of said piston, a chuck, and means for transmitting the rotative movement of the piston to said 15 chuck to rotate the latter, including a power transmitting member surrounding said element.

20. 4. A motor comprising a cylinder, a piston reciprocable in said cylinder, a member extending into one end of said cylinder and in said piston for causing intermittent rotation of the latter, a member extending into said cylinder and adapted to be rotated by said piston, a longitudinally disposed 25 shaft rotated by said member, and a tool receiving means operated by said shaft.

30. 5. A motor comprising a cylinder, a piston reciprocable in said cylinder, a member extending into one end of said cylinder for causing intermittent rotation of said piston, a member extending into said cylinder and adapted to be rotated by said piston, a longitudinally disposed shaft parallel with said cylinder rotated by said member, and a tool 35 receiving means operated by said shaft.

40. 6. In a motor, a cylinder, a hollow piston therein, cooperating means carried by said cylinder and piston for causing rotation of the latter, a chuck, means operated by the piston for rotating the chuck including an element mounted in the interior of said piston and having a straight tongue and groove connection therewith, and means for rendering said rotating means inoperative to 45 rotate said piston.

50. 7. In a motor, a cylinder, a hollow percussive piston therein, cooperating means carried by said cylinder and extending into said piston for causing rotation of the latter, a chuck, chuck rotating means including an element extending into the interior of said piston and having a straight tongue and groove connection therewith, and means to interrupt the operation of said chuck 55 to rotate means.

60. 8. In combination with a tool, a percussive motor having a cylinder and a piston, a member having a spiral tongue and groove connection with said piston, a stationary member, a ratchet and pawl connection be-

tween said members, a member having a straight splined connection with said piston, and means including power transmitting gearing to transmit rotation from said last mentioned member to said tool. 70

9. In combination with a tool, a percussive motor having a cylinder and a hollow piston therein, a member projecting into said hollow piston and having a spiral tongue and groove connection therewith, a member adapted to cooperate therewith, a ratchet and pawl connection between said members, means to hold or release said second mentioned member at will, a member having a straight splined connection with 80 said piston, and means including power transmitting gearing to transmit rotation from said last mentioned member to said tool.

10. In combination with a tool, a percussive motor having a cylinder and a hollow piston reciprocating therein, a member projecting into said hollow piston and having a spiral tongue and groove connection therewith, a member normally held stationary, means to release said last mentioned member at will, a ratchet and pawl connection between said first and second mentioned members, a member having a straight tongue and groove connection with said piston and projecting thereinto and surrounding said first mentioned member, and means to transmit rotation from said last mentioned member to said tool. 85 90 95

11. In a motor, a cylinder, a hollow percussive piston therein, cooperating means carried by said cylinder and extending into said piston for causing rotation of the latter, a chuck, chuck rotating means including an element extending into the exterior of said piston and having a straight tongue and groove connection therewith, and means to interrupt the operation of said chuck including manually adjustable friction means. 100 105

12. A motor comprising a cylinder, a piston reciprocable in said cylinder, a member extending into one end of said cylinder for causing intermittent rotation of said piston, a member extending into said cylinder and adapted to be rotated by said piston, a longitudinally disposed shaft parallel with the axis of said cylinder and rotated by said member, and a tool receiving means operated by said shaft. 110 115

13. In a motor, a cylinder, a hollow percussive piston therein, cooperating means carried by said cylinder and projecting into the interior of said piston to impart to said piston alternate straight and spiral movements on alternate strokes, and tool rotating means including an element projecting into said piston, and power transmission gearing operated by said piston during its spiral movement. 120 125

14. In a motor, a cylinder, a hollow per-

cussive piston therein, cooperating means carried by the cylinder and projecting into the interior of said piston to impart to said piston alternate straight and spiral movements on alternate strokes, and tool rotating means including a plurality of elements projecting into said piston and power transmission gearing operated by said elements.

15. A motor comprising a cylinder, a piston reciprocable in said cylinder, a fluted member extending into one end of said cylinder for causing intermittent rotation of said piston, a fluted member extending into said cylinder and adapted to be rotated by said piston, a longitudinally disposed shaft

parallel with said cylinder rotated by said member, and a tool receiving means operated by said shaft.

16. A motor comprising a cylinder and a rear head, a hollow rotating piston reciprocable in said cylinder and an intermittently rotating element having a portion extending into the interior of said piston, a chuck, and means for transmitting the rotating movement of the piston to said chuck to 20 rotate the latter including a power transmitting member surrounding said element and frictionally engaging said rear head.

In testimony whereof I affix my signature.

ELMER G. GARTIN.

Certificate of Correction.

It is hereby certified that in Letters Patent No. 1,574,879, granted March 2, 1926, upon the application of Elmer G. Gartin, of Claremont, New Hampshire, for an improvement in "Rotating Mechanism for Rock Drills," errors appear in the printed specification requiring correction as follows: Page 2, line 24, strike out the word "and"; page 3, line 105, claim 11, for the word "exterior" read *interior*; and that the said Letters Patent should be read with these corrections therein that the same may conform to the record of the case in the Patent Office.

Signed and sealed this 25th day of May, A. D. 1926.

[SEAL.]

WM. A. KINNAN,
Acting Commissioner of Patents.
